UNITED STATES PATENT OFFICE.

LEO H. PLEINS, OF CHICAGO, ILLINOIS, ASSIGNOR TO JAMES B. CLOW & SONS, OF CHICAGO, ILLINOIS, A CORPORATION.

RECEPTOR FOR SHOWER-BATHS.

1,017,167.

Specification of Letters Patent. Patented Feb. 13, 1912.

Application filed May 11, 1907. Serial No. 373,188.

To all whom it may concern:

Be it known that I, LEO H. PLEINS, a citizen of the United States, residing at Chicago, in the county of Cook and State of Illinois, have invented certain new and useful Improvements in Receptors for Shower-Baths, of which the following is a specification.

The object of the present invention is to provide a device for use as a substitute for the floor-slabs heretofore used in the construction of shower-bath stalls, with a view to avoiding many of the objections to which former constructions are open, and to this end the invention consists in the features of novelty that are hereinafter described.

In the accompanying drawing which is made a part of this specification; Figure 1 is a perspective view of the lower portion 20 of a shower-bath stall having a receptor embodying the invention, the upper portions of the walls of the stall being broken away. Figs. 2 and 3 are, respectively, a transverse and a longitudinal section thereof in vertical 25 planes passing centrally through the drain opening. Fig. 4 is a plan view of the improved receptor.

The improved receptor comprises a foot-slab, A, and a part, B, hereinafter called a wall-base, by which the foot-slab is bounded. The foot-slab is imperforated, save for a drain opening, a, formed through it and preferably located near the back thereof, and its top side slopes from the four sides, 35 respectively, toward said opening. The wall-base extends above the margins of the foot-slab and has in its top side a groove, b, resulting in parallel flanges, b', which extend above the foot-slab and are adapted to 40 receive between them the lower edges of the slabs, C, which form the walls of the stall. The groove or space between the flanges, is slightly greater in width than the thickness of the slabs, C, so as to leave 45 a space which is filled with a suitable cement made, say, of litharge and glycerin, by which an absolutely tight joint between the wall-slabs and the receptor is made. If desired, the receptor may be grooved only 50 at its two sides and back, but I prefer to groove it also at the front for receiving the lower edge of an extension-sill, C', for preventing water from splashing out through the open front of the stall, when 55 the front curtain is drawn. The wall-base

also extends below the margins of the inwardly sloping foot-slab and the top and bottom sides of the foot-slab are preferably parallel, resulting in a dead-air space D. In order to support and strengthen the 60 foot-slab it is provided on its under side with ribs, a', the bottoms of which lie in the plane of the bottom of the wall-base and divide the dead-air space into a number of 65 separate cells.

The entire receptor is water tight, save for the drain opening, and is preferably made in a single, integral piece of porcelain glazed on its exposed surfaces, so that every integrant part of the integral structure braces and strengthens every other part and absolutely prevents their relative movement or displacement.

The improved receptor affords means for making an absolutely water tight stall which 75 may set directly on top of the floor as shown in Fig. 1, or completely below the floor as shown in Fig. 2, or partly in the floor as shown in Fig. 3. One of its chief advantages over a floor-slab as heretofore used 80 lies in the fact that being water tight enables it to be used in any of the ways above described and on any floor of a building without danger of wetting the floor with consequent injury thereto and to the ceiling 85 below.

It has been attempted to prevent the leakage which has inevitably taken place between the floor-slab and walls of the stall, as heretofore arranged, by using a sheet of 90 lead extending beneath the entire floor-slab and having its edges bent upward at the edges of the floor-slab, but this has been found in practice to be inadequate because, in time, the floor-slab inevitably ruptures 95 the sheet lead and permits the water to escape. It has been found also that more or less sweating takes place between the sheet lead and the floor upon which it rests because of the condensation of the moisture 100 carried by the air in the space between the sheet lead and the floor, this space, although slight, being open to atmosphere. The space referred to is due to the inevitable irregularities in the surface of the sheet 105 lead and in the surface upon which it rests, it being impossible to make their extensive surfaces absolutely flat. This objection is obviated by the improved receptor because of the limited area of the surfaces of contact 110

between the wall-base of the receptor and the floor. With such limited surfaces of contact a more perfect seating of the receptor is possible than where the surfaces 5 of contact are co-extensive with the floor-slab. Furthermore, dead-air being a poor conductor of calorific the changes in temperature to which the foot-slab is subjected are not so freely transmitted to the floor as they 10 would be if the slab contacted with it throughout its entire extent, and therefore expansion and contraction of the floor is materially lessened. But one of the most important advantages which the improved 15 receptor has over a floor slab as heretofore used, is the absolute rigidity, relative immovability and water tight union of the several integrant parts, there being no joints between them that can open and cause leakage, which is bound to occur in course of 20 time.

What I claim as new and desire to secure by Letters Patent is,—

As a new article of manufacture, a recep-

tor for shower baths having an imperforated 25 foot-slab provided with a drain opening, and a wall-base bounding the foot-slab and extending both above the upper and below the lower surfaces of the slab, the wall-base being provided in its top side with a groove 30 resulting in parallel flanges extending above the upper surface of the foot-slab and adapted to receive between them and confine the lower edges of wall slabs, the foot-slab being provided on its under side with strengthening 35 and supporting ribs resulting in dead air spaces bounded by the downwardly extending portions of the wall-base, the several integrant parts of the receptor being rigid and the entire receptor being made in 40 a single integral piece, whereby the several integrant parts of the receptor are united without joints or seams.

LEO H. PLEINS.
